UNITED STATES PATENT OFFICE.

ERNEST M. GLASGOW, OF TOWACO, NEW JERSEY, ASSIGNOR TO RUSSELL & STOLL COMPANY, OF NEW YORK, N. Y., A CORPORATION OF NEW YORK.

SNAP SWITCH.

Original application filed February 9, 1924, Serial No. 691,606. Divided and this application filed October 23, 1924. Serial No. 745,270.

My invention relates to electric switches and more particularly to a construction of snap switch mechanism wherein the snap switch spring is normally substantially without tension but is put under tension by movement of the handle or other shaft in either direction to wit: to either open or to close the switch. The invention also relates to the special snap switch devices whereby the switch arm is held locked during the winding up of the spring, said latch devices acting for movement of the switch arm in either direction.

The object also is to so construct the snap switch mechanism that the switch will be positively locked in each of its positions and yet the mechanism will be ready to function and produce the snap action when the operating lever or shaft is turned. By this positive locking an accidental movement of the switch by a severe knock or jar is prevented.

The novel construction of snap switch herein described and claimed is set forth in my original application for patent filed February 9th, 1924, Serial No. 691,606 for safety switch and enclosure of which the present case is a division.

My present invention relates more particularly to the snap switch action and consists in the improved construction and details hereinafter set forth wherein the features and general objects above set forth are realized.

In the drawings:

Fig. 1 shows the apparatus in plan view. Fig. 2 is a side elevation of the parts as mounted on the under side of an insulating plate which is removed in Fig. 1 to expose the mechanism.

Fig. 3 is an end elevation.

Fig. 4 is a plan of the insulating plate as preferably equipped with fuse clips and contacts after the manner described and claimed in my original application.

Fig. 5 is a vertical section of Fig. 4 on the line 5—5.

1 indicates the switch box, 2 the cover pivoted for instance at 3 on one side and held down by a clamp nut 4 at the other side (see Figs. 1 and 2). The operating shaft shown at 5 is provided with a handle 6 and may be turned by the latter in either direction, to throw the switch from "on" to "off" or vice versa. Said shaft is mounted

to be capable of turning in suitable bearings 55 consisting for instance of bosses 5' projecting from the inner face of the wall of the casing. Between said bearings 5' the shaft is mounted and turns in a pair of brackets 5'' which depend from a plate or frame 9' secured to the lower face of an insulating slate or other base 9. Said base 9 is suitably supported by lugs or other means within the casing at a point preferably below and sufficiently removed from the top edge thereof 60 to afford space for the fuse and fuse clips supported directly thereon and carries on its under face all of the switch contacts of the snap switch together with the switch blades or similar members co-operating 70 therewith and likewise the snap switch mechanism to be presently described.

The switch arm or arms supporting the blades of the switch consist preferably of a pair of arms 11 suitably fulcrumed to be 75 capable of turning independently of the handle-actuated shaft 5. In the present instance said arms are, for compactness and simplicity of structure, fulcrumed on the shaft 5 itself between the brackets 5'' and said arms are connected by a cross member or rod 11' to insure the rigidity of the switch arm thus constructed.

The switch blades of any desired number are indicated at 7. These are bolted or secured in any other suitable manner to the sides of the arm 11 and are insulated from one another and from the bolts or studs supporting the same in the well known manner by bushings, disks and spacers or by other 85 suitable means. The contacts with which the blades co-operate to close the circuit are indicated at 8 and comprise preferably pairs of springs each pair of which projects from a block of metal properly secured to the under side of the insulating plate 9 so that the pairs of springs will project downwardly from said base. The switch blades 7 enter between the pairs of springs 8 to close the circuit. These members 8 and 7 act 90 after the manner of the knife blades and spring contacts of the ordinary knife switch.

From the shaft 5 projects an arm 12 keyed to the shaft 5 and pivotally connected to or linked up with a link 13 the pivotal connection or pivot pin being extended laterally as indicated at 13'. (See Fig. 1.) The link 13 terminates in or carries a cross

pin 14 which engages slots 15 in the switch arms 11. These slots 15 are elongated in a direction to permit limited lost motion of the link 13 and operating shaft 5 when the latter is turned by the operating handle. The pin 14 is coupled to the switch arm by engagement with the sides of the slot and acts as a dog to hold the switch arm 11 from movement under the influence of the snap action spring while the spring is being put under tension as will be presently described, said dog for this purpose co-operating with a suitable stop from which it is disengaged under the action of the turning movement 15 of the shaft 5 in winding up the snap action spring.

The stop device consists of a pair of stop latches 19, 19' one of which holds the dog and switch arm 11 temporarily when the shaft 12 is turned to open the switch, while the other acts on the reverse movement whereby the switch is closed. The snap action spring is indicated at 16 and is wound around the main operating shaft 5. The tension of the spring is materially increased by movement of the shaft in either direction. The free extremities of the spring are operatively connected respectively with the switch arm 11 in any desired way to act 25 respectively on the same in opposite directions. Thus, for instance, one free end thereof may hook on top of one of the pair of switch arms 11 to move them in one direction while the other free end hooks underneath one of said arms and is thereby operatively connected with the compound switch arm to actuate said arm in the opposite direction.

The winding up action of the spring is secured by engagement of the ends of the pin 13' therewith. One end of said pin engages the spring on its upper side and the other engages it on its under side. As will be obvious, the turning of the arm 12 secured 40 to the shaft 5 in a downward direction, for instance, will wind up one end of the spring by engagement of one end of pin 13' with the top side of the spring, while the other end of the spring being hooked on top of the switch arm will apply the snap spring action to the arm 11 when the arm is released by disengagement of the dog from the stop or catch with which it is engaged until withdrawn from engagement by the movement 45 thereof in the slot inward toward the shaft 5 by the action of the link 13. The other end of pin 13' engaging under the opposite end of the spring will, on turning of the shaft in the opposite direction, wind up said end while the opposite end which hooks under the arm will throw it in the opposite direction when the arm is released by disengagement of the pin or dog 14 from the latch or stop which normally opposes the movement until, in the winding up move-

ment of the shaft, said dog has been drawn inward toward the shaft away from engagement with said stop or latch. The stop or latch devices engaged by the dog 14 are two in number and are preferably constructed 70 and mounted as follows:—

A fixed support for the same comprises preferably the fixed bracket or yoke 17 which may be cast in one piece with or properly secured to the supporting plate 75 9' and projects in a downward direction from the insulating plate 9, as shown. These latches or stops consist of a pair of shouldered plates 19, 19', the former of which is pivotally supported between the arms of the yoke or bracket 17 near the lower end thereof, while the other plate 19' is mounted on a pivot or pivotal support extending between the arms of the bracket near the upper end thereof, as shown clearly in Figs. 2 and 3. The plates 19, 19' are adapted to swing freely and independently of one another in said fixed bracket or yoke 17 and are connected to one another by a spring 18 which normally tends to project the latches 90 into position so that the dog 14 will engage and be locked by one or the other of them as shown in the case of latch 19. One of said latches, to wit, the latch 19, locks the dog 14 while the spring is being wound up preparatory to a throwing of the switch to open position, while the other latch or stop 19' similarly locks the dog and switch arm during the winding up action of the spring by the shaft 5 preparatory to the movement 95 of the switch to closed position. A pin 20 supported in the yoke 17 passes transversely through an opening in the latches 19, 19' and serves as a stop pin to limit their motion 100 supported in the yoke 17 passes transversely through an opening in the latches 19, 19' and serves as a stop pin to limit their motion under the action of the spring 18. When the dog is disengaged from the shoulder of the latch or stop by which it is locked, it passes freely over the inclined side of the other latch until it reaches position to permit the latch to spring out so that the shoulder thereof will pass over the dog 14 and the latter will be thereafter locked by said latch until the dog is again withdrawn from locking position.

As described and claimed in my prior application the top of the insulating plate may carry pairs of springs 8' which are mounted upon and project upwardly from the base 9 and constitute clips for the fuses 8''. These clips 8' are suitably connected with the bases of the double contacts 8, as will be presently described, and in such manner that when the switch is operated to disconnect the service or local line from the main line, both fuse terminals will be also disconnected so that the fuses may be then removed and a new fuse substituted without danger of shock from leakage back from the local or service line in case the service line may have become crossed with some other line or circuit.

cuit and also with the obvious effect of protection from shock from the main line.

Also, as will be seen, all of the switch terminals are effectively shielded from accidental contact as described and claimed in my prior application by reason of the fact that they project from the under side only of the insulating plate 9 and are not in any manner exposed when the cover 2 of the box is removed for the purpose of substituting a fuse.

The drawing Fig. 2 shows the switch in closed position. The turning of the handle shaft 6 to throw the switch arm to "off" position winds up the snap action spring 16 and finally withdraws the dog 14 from locking position on the shoulder of the latch 19. Thereupon the switch arm is thrown by the action of the spring which is being placed under tension while winding up one end thereof. The switch now assumes the "off" position indicated in dotted lines and the dog 14 is locked under the shoulder of the other latch. A reverse movement of the shaft 5 by the handle 6 to close the switch now winds up the opposite end of the spring until during the winding movement, the dog has been pulled in toward the shaft 5 sufficiently to be disengaged from the shoulder of the second latch 19' whereupon the spring, by engaging under the switch arm by its opposite hooked end, throws the arm back to the closed position.

Secured in the bottom of the box 1 is a slate or other insulating base 30 on which are mounted connecting blocks 31, 31', for attachment of the main line or service or local cables. From these blocks extend the interior cables 32, 32' whose free ends beneath the slate base 9 are fastened to the conducting blocks which carry respectively the various line and service contacts 8 of the knife switch, said blocks being attached to the under side of the slate base 9 and having the spring contacts 8 projecting therefrom downwardly away from the base. One of the two openings in the end of the box through which the main line and local cables may be introduced for attachment to the connecting blocks 31, 31' is indicated at 33. For convenience of attachment, the connecting cables 32 within the box are used as the main line connecting cables and the cables 32' as connecting cables from the local or service line, although a reverse arrangement might be employed using the connections 32 as the local or service line connections. Assuming that the latter are used as the main line connections and the cables 32' as the service line connections, the connection to the various switch contacts may be made by attachment of the cable ends to the blocks carrying said switch contacts in the order or arrangement indicated in Fig. 4 where the various switch contacts

and blades beneath the slate base 9 are indicated in dotted lines. Two fuse clips 8' at one end of the slate base and rising therefrom are located opposite one of the two contacts 8 at the same end of the base and are in immediate connection therewith through the screws or bolts 34 which fasten the base blocks for said contacts and clips to the opposite face respectively of the slate base 9. At the other end of the slate base 9 fuse clips 8' are fastened directly to the upper face of the base by the screws 34'. Connection is established between them and the contacts 8 with which the blades 7 cooperate to close the connection from the main line terminal switch contacts 8, by means of straps 35 fastened by means of the screws 34' under the block from which the fuse clip rises, and at the other end fastened down upon the upper face of the block by a screw 36 which extends through the base and fastens the local or service line switch contact 8 to the under surface of the slate base.

The connection thus established through the switch contacts, the blades, fuse clips and the fuses may be readily traced by the arrows and the result of the arrangement is that when the blades each sever connection with its pair of contacts 8, not only is the connection between the main line and the local or service line interrupted at two points but the fuse clips 8' are disconnected from both the main line and the service or local line thereby permitting the fuses to be substituted without danger. Moreover, inasmuch as all the main line and service line contacts of the switch are arranged on the under side of the base 9 and project downwardly therefrom there is no possibility of contact therewith by the hand of the operator.

The features last described form the subject of claims in my prior application.

What I claim as my invention, is:—

1. In a snap switch, the combination with a switch arm, of an operating shaft, a link connected with the arm by lost motion and provided with a dog, an arm extending from the shaft and adapted to move said link with lost motion, a spring acting on the arm and normally restrained from operation by said dog and a catch adapted to hold the dog and arm against movement until the dog performs lost motion under the action of the operating shaft.

2. In a snap action switch, the combination of a pivoted switch arm, a dog-carrying link engaging the arm with lost motion, an operating shaft having an arm connected with the link and two catches mounted on a fixed support and having dog-engaged shoulders reversely arranged by which the switch arm may be held in either "on" or "off" position and, in its movement from one

- position to the other after being freed by release of the dog from the shoulder of one catch, may pass to position for engagement of the dog on the shoulder of the other catch. 70
3. In a snap action switch, the combination of a pivoted switch arm, a link provided with a dog engaging said arm with lost motion, an operating shaft having an arm connected with the link, and two catches mounted on a fixed support and having dog-engaged shoulders reversely arranged by which the switch arm may be held in either "on" or "off" position and, 75
- 10 15 in its movement from one position to the other after being freed from the shoulder of one catch, may automatically pass to position for engagement on the shoulder of the other catch. 80
- 20 4. In a snap action switch, the combination of a pivoted switch arm, a link provided with a dog engaging said arm with lost motion, an operating shaft having an arm connected with the link, and two catches 85 mounted on a fixed support and having dog-engaged shoulders reversely arranged by which the switch arm may be held in either "on" or "off" position and, in its movement from one position to the other after being freed from the shoulder on one catch, may automatically pass to position for engagement on the shoulder of the other catch, said catches being pivoted to move independently 90
- 25 30 35 of one another on a fixed support and being connected with one another by a spring operating to move the catches into position for engagement of the dog with their shoulders. 95
5. In a safety switch, the combination of a switch, an operating shaft provided with a handle, an arm extending from said shaft, a link pivotally connected to said arm and provided with a dog having lost motion connection with the switch, an automatic catch 100
- 40 45 for engagement with said dog to hold the switch against movement, a spring operatively connected to said switch and means connected to the operating shaft for winding said spring in the act of moving the dog from engagement with the catch. 105
- 50 6. In a snap switch, the combination of a contact carrying switch arm, a dog normally holding said switch arm against movement carried by and movably mounted on said switch arm, a stop for said dog, an operating shaft carrying a handle, means connected with the operating shaft for moving said dog from engagement with its stop to permit the arm to move, a coiled spring coiled around said handle-carrying shaft 110
- 55 60 65 and engaged at its two free ends respectively with opposite sides of the contact carrying switch arm and means acting on opposite ends of said spring respectively on movements of the operating shaft in opposite directions to wind said spring. 115
7. In a snap switch, the combination of an operating shaft provided with a handle, a switch arm fulcrumed on said shaft, a spring coiled on said shaft and adapted to act upon said arm in opposite directions and move the same, an arm extending from the shaft, a dog linked to said arm for freeing the switch arm and releasing it to the action of the spring when the shaft is turned and means connected with the shaft for putting said spring under tension upon movement of the shaft in either of the directions of movement imparted to the same for the purpose of opening or closing the switch. 120
8. In a snap switch, the combination of a slotted switch arm, switch blades mounted thereon, a spring connected at both ends to the arm and adapted to act upon said arm in opposite directions and move the same, a dog engaged directly with the slot in the arm, a stop for said dog, an operating shaft and means for moving the dog in the slot to free it from the stop and at the same time putting said spring under tension upon the movement of the shaft in either of the directions of movement imparted to the same for the purpose of opening or closing the switch. 125
9. In a snap action electric switch, the combination with a rock shaft, a pivoted switch arm carrying the switch blades and provided with a slot, a dog engaging in the slot of said arm and thereby operatively connected therewith, a stop with which said dog is normally engaged to restrain the switch arm from movement, a spring operatively engaged with the switch arm, means for putting tension on the spring by a rocking movement of the shaft and means operatively connecting said shaft and dog for moving the same in the slot during the winding of the spring to move the dog in the slot in a direction to disengage it from the stop. 130
10. In a snap action switch, the combination of a slotted switch arm and switch blades carried thereby, a dog working in said slot, a stop engaged by said pin, a spring engaged with the switch arm and a rock shaft operatively connected to the spring to put the same under tension and means for operatively connecting the shaft with the dog to move the dog in the slot of the switch arm in the action of putting the spring under tension. 135
11. In a snap action switch, the combination of a switch arm, a dog operatively engaged with the arm to restrain it from movement and movably mounted thereon, a latch engaged by the dog, a spring operatively connected with the switch arm and means for placing said spring under tension to operate the arm and at the same time actuate the dog to move it on the arm and disengage it from the latch. 140
12. In a snap action switch, the combina- 145

- tion of a switch arm, a dog operatively engaged with the arm to restrain it from movement and movably mounted thereon, a pivoted latch engaged by the dog, a 5 spring operatively connected with the switch arm and means for placing said spring under tension to operate the arm and at the same time actuate the dog to move it on the arm and disengage it from the latch.
- 10 13. In a snap action switch, the combination of a switch arm, a dog operatively engaged with the arm to restrain it from

movement and movably mounted thereon, a pair of latches adapted to be engaged by the dog, a spring operatively connected with 15 the switch arm and means for placing said spring under tension to operate the arm and at the same time actuate the dog to remove it from engagement with each latch.

Signed at New York in the county of 20
